CLAIM

We claim the ornamental design for an ink tank with RFID sensor and serpentine vent, as shown and described.

DESCRIPTION

FIG. 1 is a perspective view of the ink tank with RFID sensor and serpentine vent showing the new design;

FIG. 2 is a top plan view thereof;

FIG. 3 is a bottom plan view thereof;

FIG. 4 is a front view thereof;

FIG. 5 is a rear view thereof;

FIG. 6 is a left side view thereof; and

FIG. 7 is a right side view thereof.
